UNITED STATES PATENT OFFICE

165,078

FRAME FOR BARBER'S SEAT

Ben Klein, Santa Monica, Calif.

Application September 11, 1950, Serial No. 12,137

Term of patent 14 years

(Cl. D15—8)

To all whom it may concern:

Be it known that I, Ben Klein, a citizen of the United States, residing at Santa Monica, State of California, have invented a new, original, and ornamental Design for a Frame for Barber's Seat, of which the following is a specification, reference being had to the accompanying drawing, forming a part hereof.

Fig. 1 is a perspective view of a frame for barber's seat embodying my new design.

Fig. 2 is a bottom plan view thereof.

Fig. 3 is a side elevational view.

Fig. 4 is a front elevational view.

The dominant features of my design are shown in full lines in the drawing.

I claim:

The ornamental design for a frame for barber's seat, as shown and described.

BEN KLEIN.
